Primary Examiner — Vy N Koenig(74) *Attorney, Agent, or Firm* — Andrew C. Cheng(57) **CLAIM**

The ornamental design for a frame for fixing camera, as shown and described.

DESCRIPTION

FIG. 1 is a front view of a frame for fixing camera according to the present design;

FIG. 2 is a rear view of the frame for fixing camera of FIG. 1;

FIG. 3 is a left view of the frame for fixing camera of FIG. 1;

FIG. 4 is a right side view of the frame for fixing camera of FIG. 1;

FIG. 5 is a top view of the frame for fixing camera of FIG. 1;

FIG. 6 is a bottom view of the frame for fixing camera of FIG. 1; and,

FIG. 7 is a perspective view of the frame for fixing camera of FIG. 1.

The broken lines shown in the drawings depict features of the frame for fixing camera that form no part of the claimed design.
